OIL BATH ROTARY

Sergius C. Fietinghoff, Los Angeles, Calif., August
R. Maier, Dallas, Tex., and Cyril F. Van
Loozen, Los Angeles, Calif., assignors to Oil
Well Supply Company, a corporation of New
Jersey

Application January 11, 1940, Serial No. 313,456

5 Claims. (Cl. 184—6)

This invention relates to improved lubricating means for a rotary of the type used for drilling vertical holes in the surface of the earth. While not limited thereto, the present invention is particularly directed to features of improvement over the type of rotary shown in the patent granted to August R. Maier, No. 2,073,559, dated March 9, 1937.

It is old in the art, as exemplified by said Maier patent, to utilize centrifugal force of the rotating members to elevate oil and throw it over the edge of the retaining wall. In the type of rotary exemplified by the Maier patent, oil is normally picked up by dipping the teeth of the pinion shaft in an oil reservoir formed in the stationary portion of the housing. This lubricant is carried upward into contact with the teeth on the underside of the rotating table, from which it flows downwardly over the antifriction bearing. Part of the lubricant flows from this bearing back directly into the oil reservoir and part is directed downwardly over the hold-down bearing which has to be returned to the oil reservoir in some manner. It is to the means for returning the oil collected in the sump of the rotating members to the reservoir in the stationary member that the present invention is directed.

It has been found that when a rotary such as that shown in the Maier patent operates at certain speeds, oil is lost by escaping between the rotating and stationary members instead of returning to the reservoir. Accordingly, it is an object of the present invention to provide means for effecting a more positive return of oil to the reservoir.

Another object of this invention is to provide means for protecting the oil from contamination as a result of a blowout from beneath the rotary.

A further object is to provide means to prevent the accidental dropping away of the annular ring attached to the bottom of the rotating member. For a full and complete understanding of the invention, reference is to be made to the accompanying drawings, the following detailed disclosure, and the appended claims.

In the drawings,

Figure 1 is a plan view of a rotary embodying the present invention;

Figure 2 is a vertical longitudinal section thereof taken on line II—II of Figure 1, and

Figure 3 is an enlarged fragmentary detail of the parts shown in Figure 2.

Referring more particularly to the drawings, the invention is illustrated by way of example, as applied to a rotary having a base 10 and a table 11 rotatably supported on the base by means of antifriction bearings 12. The base 10 has an upstanding outer wall 13 extending upwardly to the under face of the table 11 and an inner wall 14 upon which the bearing 12 is supported and 60

forms between the inner and outer walls an annular oil channel or lubricating reservoir 15. The inner wall 14 also has a depending flange 16 carrying a hold-down bearing 17 through which there extends downwardly from the table 11 an inner collar 18. The upper base of the table 11 extends outwardly to the upper edge of the wall 13 and slidably joins the latter in an inner locking seal 19 to prevent the in-flow of water or mud. This seal is further protected by a rotary guard 20 mounted on the wall 13. The table 11 carries a master bushing 22 or spiders 21 and 23 which serve to grip and hold a drill pipe extending downwardly therethrough.

15 An extension 24 extends from the outer wall 13 in which is mounted a shaft 26 which is driven from an external source through a sprocket 27 mounted on the shaft 26. A bevel gear 29 is keyed on the end of the shaft 26 extending within the wall 13. This gear 29 dips into the lubricant carried in reservoir 15 and engages with an annular bevel gear 30 mounted on the lower surface of the table so that lubricant from the lower reservoir 15 is carried up into contact with the teeth on table 11. This lubricant drips downwardly into bearing 12 and ultimately is returned to reservoir 15.

It will be understood that the above construction is of a typical rotary and that this invention may be applied to rotaries deviating from the above in details of construction.

In the apparatus embodying the present invention, a portion of the lubricant passes downwardly through the frictional bearing 12 and then into a hold-down bearing 17, from which it passes between the hold-down bearing 17 and collar 18 where it is gathered in a sump from which it is returned to the reservoir 15. This sump is formed below the hold-down bearing 17 by means of an annular ring 31 secured to the bottom edge of the collar 18 by means of screws 32 and has an upwardly extending wall encircling the depending flange 16 of the base 10. An annular trough member 34 is removably attached to the base 10 by means of bolts 36 in cooperative relationship with the annular ring 31, so that any oil flowing over the top of the flange 33 of the sump falls into said trough member 34, from which it passes through passageway 35 cored in the wall of the base 10 to the oil reservoir 15. This passageway is of sufficient depth that the oil in reservoir 15 passes therethrough at all times in order that it will be practically impossible to stop the return of fluid to the reservoir 15. Since the annular trough is removably attached to the base 10, a drain (not shown) can be used to remove the oil before removing member 34. Likewise, a washer or oil seal 37 could be conveniently placed about bolt 36 in order to prevent any loss of oil.

In the prior art oil was forced by centrifugal action over the top of member 33 where it was caught by trough 34 as shown in Maier Patent No. 2,073,559. At slow speeds of the Maier rotary, oil was found to leak out between these two members, as they did not overlap or overhang due to the method of assembly which made it impossible. Likewise, if the sump overflowed, which is likely to occur on stopping of the rotary or for other reasons, oil was caused to escape between these two members. Furthermore, if the passageway 35 became clogged, oil was forced out of the member 34 between the two members 34 and 35. Occasionally a blowout occurred which forced foreign matter up between the ends of the flange and the bottom of the base of the Maier apparatus, fouling the oil in the reservoir 15.

In the apparatus of the present invention, an overhanging lip 40 is formed at the upper edge of upstanding wall 33 of the ring member 31, which overlies a cooperating under-lip 41 located in the upper portion of the trough member 34 above the oil level of the oil reservoir 15. This construction and arrangement forms an oil breather which is effective to prevent a vapor lock from forming and to prevent the return of the lubricant to the reservoir 15. With this type of lip construction, oil is prevented from flowing out between members 33, 34 when member 33 is rotating, even at relatively low speeds, and also when member 33 is stationary. Member 34 is also in cooperative relationship with the under side of member 33, as shown by extending section 42 of member 34. As thus constructed and arranged, member 33 is prevented from dropping down due to an accident caused by the failure of bolts 36, in which event member 34 serves as a guard, and thus functions as a safety device. Member 34 also prevents the dropping of member 31 when making repairs which require the removal of the ring portion of the rotating member. As an additional safety precaution in the event of a blowout, a labyrinth form of seal is provided, as shown, between the stationary member 34 and the rotating member 31.

Thus, in returning the oil gathered in the sump of the rotating member to the reservoir in the stationary member, two members, 31 and 34, are provided for preventing the leakage of any oil, that not only assure positive return of the oil at both low rotative speeds and even when stationary, but also assist in preventing contamination of the oil by foreign substances forced against the under side of the rotary such as occurs in the event of a blowout.

While we have described quite precisely the characteristics of the particular embodiment of our invention herein illustrated, it is to be understood that various modifications may be made without departure from the invention as defined in the appended claims.

We claim:

1. In a rotary, a lubricant reservoir in said rotary, means in the rotatable member for receiving oil, and a stationary member removably attached to said rotary in cooperative relationship with said rotatable member for returning oil from said receiving means to said reservoir, said members having coacting sealing means thereon preventing ingress of foreign substances between said members.

2. A rotary comprising a rotating table having

a downwardly depending sleeve, a bearing about said sleeve, a lubricant reservoir in the base of said rotary, gearing for driving said table and carrying lubricant from said reservoir into said bearing, a sump carried by said sleeve to receive said lubricant passing through said bearing, the sump having an upper overhanging lip above the liquid level in said reservoir over which lubricant may pass in returning to said reservoir, and a member 10 removably attached to the base of said rotary and having an upright portion disposed immediately beneath said overhanging lip for returning the lubricant passing over said overhanging lip, said member having a portion thereof extending beneath the sump.

3. A rotary comprising a rotating table having a downwardly depending sleeve, a lubricant reservoir formed in the base of said rotary, an annular ring attached to said sleeve forming a sump for receiving lubricant having an upper 20 overhanging lip edge above the liquid level in said reservoir, and an annular member attached to the base of said rotary for returning lubricant passing over the lip of the sump having one lip 25 underlying the overhanging lip and a second lip in cooperative relation with the under side of said annular ring for retarding the passage of foreign matter therebetween which is thrust against the bottom side of the rotary.

4. A rotary including a rotatable table, a stationary base having a lubricant reservoir therein, a hold-down bearing for the table, means supplying lubricant to said bearing, and means between said bearing and reservoir for effecting 30 a flow of lubricant from the bearing to the reservoir, including an outer annular member secured to the base adjacent the reservoir, an inner annular member secured to the table adjacent the hold-down bearing and providing a lubricant 35 sump for receiving lubricant from said bearing, the inner member having a terminal lip outwardly overhanging the outer member for centrifugal discharge of lubricant from the sump over said outer member to the reservoir, said inner and 40 outer members having annular coacting sealing 45 portions disposed below and preventing the ingress of foreign matter between said members.

5. A rotary including a rotatable table, a stationary base having a lubricant reservoir therein, a hold-down bearing for the table, means supplying lubricant to said bearing, and means between said bearing and reservoir for effecting 50 a flow of lubricant from the bearing to the reservoir, including an outer annular member removable 55 secured to the base adjacent the reservoir, an inner annular member removably secured to the table adjacent the hold-down bearing and providing a lubricant sump for receiving lubricant from said bearing, the inner member having a terminal lip outwardly overhanging the outer member for centrifugal discharge of lubricant from the sump over said outer member to the reservoir, said inner and outer members having annular coacting sealing portions disposed below 60 and preventing the ingress of foreign matter between said members, the inner member being removable from the table upon removing the outer member, to thereby permit access to the hold-down bearing.

SERGIUS C. FIETINGHOFF.
AUGUST R. MAIER.
